UNITED STATES PATENT OFFICE.

CARL O. BURTON, OF DULUTH, MINNESOTA.

TRACK SANDER.

1,425,575.

Specification of Letters Patent. Patented Aug. 15, 1922.

Application filed February 18, 1922. Serial No. 533,320.

To all whom it may concern:

Be it known that I, CARL O. BURTON, a citizen of the United States, residing at Duluth, in the county of Saint Louis and State of Minnesota, have invented certain new and useful Improvements in Track Sanders, of which the following is a specification.

This invention relates to a new and improved track sander and more specifically to an electrically operated sanding device adapted for use in connection with the sanding of rails upon which wheeled vehicles travel.

15 The sander of the present application has been shown and generally described in my prior Patent, No. 1,383,286, issued July 5, 1921 for automatic bridge control. In that patent it has been shown as used to sand 20 rails adjacent the wheels of an ore or coal bridge. While it is particularly adapted to that use, it is capable of use in connection with any wheeled vehicle.

In connection with sanders as used upon various types of vehicles, it is often most necessary to use the sand in freezing weather when the rails become slippery with ice. At such times, if there is any dampness in the sand, the sand tends to freeze in the sand 30 reservoir and hence does not flow.

It is an object of the present invention to provide a track sander which is adapted for distant control and which is provided with a positively opening and closing valve.

35 It is a further object to provide a device of this character in which the valve is electrically operated.

It is an additional object to provide a device in which means are provided for preventing the freezing of the sand.

40 Other and further objects will appear as the description proceeds.

Broadly, my invention comprises a sand hopper or reservoir having its lower surface 45 sloping toward a discharge opening which discharge opening is controlled by a positively operated valve. In the preferred form, this valve is operated by means of a solenoid and is adapted for distant control.

50 The reservoir is provided with heating means which, in the preferred form, consist of electric heating elements extending down throughout approximately the full depth of the receptacle.

I have illustrated a preferred embodiment 55 of my invention in the accompanying drawings, in which—

Figure 1 is a side elevation of the complete track sander assembly;

Figure 2 is a view of Figure 1 as seen from 60 the right;

Figure 3 is a vertical section showing the interior mechanism of the sander;

Figure 4 is a plan view of Figure 3 with 65 the cover removed; and

Figure 5 is a view taken on line 5—5 of Figure 3.

Referring now particularly to Figures 1 and 2, the sander container 7 is shown supported upon the frame 8. The container is 70 provided with the cover 9 and with the discharge pipe 10 leading downwardly from the container. As best shown in Figure 2, the pipe 10 is divided into two branches 11 which discharge upon the rails 12 adjacent 75 the wheels 13. The particular construction shown is that in use upon the ore bridge disclosed in my prior patent above referred to.

Referring now to Figures 3 to 5, the valve 30 seat 14 is secured to the inner side of the bottom 15 of the container 7. The pipe 10 passes through the bottom of the container and, as shown, is threaded into the valve seat member 14. Secured to and supported by 35 the member 14 is the sand directing cone 16, which forms an inner bottom upon which the body of sand rests. The support bracket 17 is secured inside the container adjacent its upper end. This bracket supports the 40 solenoid case 18 which contains a solenoid coil 19, the coil being protected by the cover 20. The inner central portion of this cover 20 is formed with a conical seat or socket 21.

The tubular plunger guide 22 is secured to 45 the solenoid case 18 in alignment with the socket 21 and with the valve seat 14. The valve closure 23 is located in the lower end of the plunger guide 22 and is adapted to fully close the opening through the valve 10 seat 14. This closure 23 is connected by rod 24 to the plunger 25, the upper end of which is adapted to fit into the socket 21 in the cover 20. The plunger 25 is formed of soft steel and is adapted to be operated upon by 50 the solenoid 19, and when so operated upon, to lift upwardly the rod 24 and thus to unseat the valve closure 23. It will be ob-

served that there is a clearance between the lower end of the guide member 22 and the cone 16 such as to permit the sand to flow out through the member 14 when the closure

5 23 is raised.

The heating elements 26 have their lower ends supported by brackets 27, which brackets are secured to the cone 16 and valve seat member 14. The upper ends of these heating elements are secured at 28 upon the outer side of the solenoid casing 18. Suitable wires 29 lead out from the upper points of connection of the heating elements and serve to conduct the current necessary to heat 10 them. The solenoid operating current is carried by wires 30 shown in Figure 4.

As best shown in Figure 4, the bracket 17 comprises a plurality of inwardly extending lugs 31 which serve to support the solenoid 20 casing 18. Intermediate these lugs 31 are open spaces 32 through which sand is introduced into the sand hopper or reservoir.

In the use of my sander, sand is placed in the reservoir by removing the cover 9 and pouring the sand in. The solenoid is fully protected by its casing and cover and the sand passes through the openings 32 until supported in the cone 16. The sand is prevented from clogging above the valve closure 30 23 by the tubular guide 22. The heat supplied by the heating element 26 prevents any freezing of the sand due to dampness contained therein.

In the operation of the sander, current is supplied to the solenoid 19 and this current causes the plunger 25 to be drawn upwardly until its upper end contacts with the seat 21. When in this position, the valve closure 23 is clear of its seat and sand flows out the lower opening and down through the pipe 10. The clearance between the lower end of the plunger guide 22 and the valve opening is made such as to permit the desired flow of sand. When it is desired to cut off the 45 flow of sand, the current in the solenoid is

thrown off and the plunger and valve closure assembly drop by gravity until the closure seats in the valve seat and cuts off the flow of sand.

My track sander as shown is simple in 50 construction and comparatively inexpensive in manufacture. It is positive in its operation and may be operated and controlled from any desired point, however distant from the location of the sand reservoir. 55

The form of construction shown is to be understood to be illustrative only as I contemplate such changes and variations as come within the scope of the appended claims. 60

I claim:

1. A rail sander comprising a sand reservoir, a discharge opening therein, a bracket located in said reservoir supporting a solenoid and a tubular guide extending in alignment with said opening, and a closure for said opening operating in said guide and controlled by said solenoid. 65

2. A rail sander comprising a sand reservoir, a discharge opening therein, a bracket located in said reservoir supporting a solenoid and a tubular guide extending in alignment with said opening, and a closure for said opening operating in said guide and controlled by said solenoid, passages being 75 provided between said bracket and solenoid to permit flow of sand thereby.

3. A rail sander comprising a sand reservoir, a discharge opening therein, a bracket located in said reservoir supporting a solenoid and a tubular guide extending in alignment with said opening, a closure for said opening operating in said guide and controlled by said solenoid, and electrical heating elements extending into the sand containing space in the reservoir. 85

Signed at Duluth, Minnesota, this 31 day of January, 1922.

CARL O. BURTON.
